ROTATING REFRIGERATING DEVICES

Donald S. Justice, Washington, D. C., assignor to Justice Industries Inc., Washington, D. C., a corporation of Delaware

Application July 2, 1951, Serial No. 234,702

12 Claims. (Cl. 62—117.5)

The present invention relates to improvements in refrigeration mechanism by simplification through the utilization of centrifugal force, and the primary object of the invention is to provide a means of refrigeration entirely without internal mechanical parts. Some other objects may be pointed out as follows:

The complete elimination of the need for internal lubricants;

An efficient arrangement of the present known adaptations of the principles of mechanical refrigeration so as to produce a device inexpensive in manufacture and highly conservative in operation;

To facilitate manufacture so as to provide a unit that may be made of metal stamping or tubing, plastic moulding, ceramic forming or other simplified assembly at low cost;

Further object is efficient low cost operation requiring only friction mounts for one rotatable shaft, which eliminates heat excess and permits the use of a minimum power drive.

Other uses and adaptations will be apparent to those skilled in the art as they follow through the detail of the drawings made a part of this specification, and in which drawings,

Figure 1 is a top plan view of the entire device without adaptation, as seen in a horizontal position. The device consists of a rotatable shaft 6 normal to and concentric with a hollow tubular ring 7, containing a refrigerant and less volatile sealer, fastened perpendicularly thereto, a second hollow ring 8, of less cubage, secured to and concentric with the first ring 7 and a third hollow ring 9, also of less cubage than ring 7, and concentrically secured to ring 8. Ring 9 contains a sealed partition block 5 (which may be omitted), followed in the direction of rotation by a tubular connector 2 extending radially from inside the periphery 10 of ring 8 into the near side 11 of ring 9. On the opposite side of partition block 5, tubular connector 1 extends from the side 11 of ring 9 closest to ring 7 to the side 12 of ring 7 farthest from ring 9. The end of tubular connector 1 adjacent to ring 7 is of U-shaped configuration so as to enter ring 7 normal to side 12.

The internal periphery 12a of ring 7 is connected to the internal periphery 10 of ring 8 by means of a conically shaped tube 3 extending in a counter-rotation-wise direction from tube 7 to tube 8. Tube 3 is widest at ring 7 and tapers to a relatively small diameter inside tube 8. Connector 3 may be further provided with a jet orifice at its termination. Ring 8 is provided with a connector from its bottom portion 13 to and through the top portion 14 of ring 7 in a manner to be described in the particulars concerning Figure 2 following. The view further shows cross member braces 15, 16 and 17 which may be added in a suitable number securing the three rings together in a fixed rotatable unit, such supports being exterior of the rings and may be set at angles to form vanes as well as acquiring rigidity for the whole

2

structure. The whole device, including connector conduits, is hermetically sealed and may have double walled cylinders with end closures substituted for rings.

Figure 2 is a schematic view showing the various conduit connections between the rings as if they occurred in one location rather than being distributed to counterbalance each other. In this regard counterbalances of metal or other suitable material may be added to any of the rings at suitable points to insure counterbalance 10 for smooth operation.

It will be noted in Figure 2 that ring 8 is elevated over ring 7 in an amount sufficient to insure flow by gravity of liquid accumulated in ring 8 returning through connector 4 to ring 7. This same connector 4 is a means of exchanging accumulated liquid from ring 8 for gas accumulated in ring 7 when the entire device is motionless and not subject to centrifugal force. At the same time connector 4 forms a U trap for liquid so that when it is subject to centrifugal force, neither gas nor liquid 20 will pass through connector 4 in either direction.

Ring 7 contains a suitable refrigerant A of comparably heavy molecular weight allowing it to readily submit itself in centrifugal force through connector 3. In centrifugal force when the liquid in ring 7 has acquired sufficient 25 rotation speed that centrifugal force has overcome the force of gravity, it will pass into connector 3 and thus create a low pressure zone around the internal diameter wall of ring 7, and thus through connector 1 low pressure is established and maintained in ring 9 to the extent 30 of the escape of liquid from ring 7. In motion, evaporation would occur on the vertically standing surface of the liquid in ring 7 but for the presence of a small amount of sealer B consisting of a liquid of less density and less volatility than the refrigerant. As an example, carbon 35 tetrachloride has been used for a volatile refrigerant and a small quantity of water as its sealer.

Connector 2 is a feeder conduit designed to introduce an evaporable amount of refrigerant into ring 9 commensurate with the low pressure created in ring 9 through 40 connector 1. For this purpose connector 2 may be extended to connect with ring 7 instead of ring 8 if desired. In this regard, however, it is well to note that any liquid emitted by connector 2 is subject to greatly increasing its evaporative surface. In the first place, 45 connector 2 may be provided with a nozzle emitting spray like droplets, as shown in Figure 3 or a fanlike stream through an elongated orifice as shown in Figure 4. In the second place it will be readily understood that in high speed rotation liquid from connector 2 will 50 be attracted to the external periphery 18 of ring 9 at a point opposite from the orifice of connector 2 and quickly spread, through the influence of rotation, along the path of rotation, internally of the peripheral of ring 9, and in this manner present a widespread evaporative 55 surface. Connector 1 is located in the rotating direction of ring 9 in advance of partition block 5 for the purpose of permitting liquid from connector 2 to have its maximum surface spread under low pressure throughout the entire ring 9 and thus give a maximum value to the cooling influence of the process of evaporation and the potential of heat absorption through the walls of ring 9.

While the foregoing explanation of drawings is of the structure, it has included function sufficiently that the whole device may be considered as operable. Particular 65 stress is made, however, on the method of operating the device as described, inasmuch as while constantly rotating no provision is made for the inevitable liquid exhaustion from ring 7 and the filling of ring 8 as pressure permits. In order to progress with the production 70 of a maximum potential of heat absorption in ring 9, it is necessary to have a repetitious action as described.

Therefore, there must be a recovery of liquid to ring 7 from ring 8 and at the same time provide a means for placing the accumulated gas in ring 7 into ring 8 so that it may be compressed and condensed for reuse. This accomplishment is made through stopping the rotation of the device when it has ceased to take liquid from ring 7 and created its maximum pressure in ring 8. On cessation of motion and while in a stop position, recovery of liquid from ring 8 to ring 7 may be expected to speedily deliver until the gas pressure in ring 8 equals the gas pressure in ring 7 whereupon gravity will take over and the liquid will pass downward through connector 4 in exchange for gas from ring 7 to ring 8. It is obvious, then, that connector 4 must be of suitable size to facilitate such movement of liquid and exchange of gas in order that the device may be started in rotation again promptly.

The provisions of the foregoing paragraph may be met through mechanical gearing so timed as to cause the motionless period, or by a thermostatically-controlled electric switch cutting off the power and re-connecting at the desired time.

It is obvious that the low pressure ring may be supplied with liquid refrigerant from ring 7 and thus placed differently in plane, and also cubaged differently, and/or arranged conically in variation.

Operation of the device in a plane other than that chosen for the purpose of this explanation may be had by alternating the speed from very fast rotation to a slow rotation just sufficient to keep liquid on the outer wall of the ring it is in, and slow enough that the centrifugal force operating in the U trap of connector 4 is overcome by the pressure created at high speed in ring 8. The high speed to motionless alteration may be used however, by use of more than one connector 4.

Adaptation of the above described device may be had in a number of ways. One method is to provide for the operation of the device with all rings standing vertical so that ring 9 only is immersed at its standing base in a liquid containing anti-freeze solution, which liquid may be circulated through coils as desired.

In the use of the device as an air-conditioner, a suggested method is using a number of units placing one device on top of another in pancake fashion and sealing the space between each of the rings 7, 8 and 9 and the corresponding ring of the unit stacked on top of it, so that the series of units form one cylindrical unit externally with two cylindrical walls internally thereof. By angling the supports 15, 16, and 17 between the rings as heretofore described so that they become vanes, air may be forced in either direction between the walls formed between rings 8 and 9, and air to cool ring 8 in the other direction between rings 7 and 8. Insulation may be used as needed. Through this method ducts may be provided so that the air cooled from rings 9 and air heated in cooling rings 8 may be conveyed as desired. In either of the described adaptors, liquid coolant may be substituted for air.

An object of the invention is the suitability of the device for adaptation in difficult space. That is to say that instead of accumulating the devices pancaked as described, they may be placed in series single file and geared to one or more power drives so that the series forms an elongated grouping that may be incorporated in flat spaces such as the walls of aircraft, ships, submarines, motor trucks, and refrigerated railway cars. To eliminate such gearing and provide independent units

of the device the shaft may be fixed instead of rotatable. The fixed shaft is made a stator for a motor with the rotor consuming the balance of the space between the stator and ring 7 and the rotor firmly attached to ring 7.

Various other changes may be made in the device and method of its operation herein presented without deviating from the spirit of the invention and limits of the following claims.

I claim:

1. In a rotating refrigerating device three tubular rings of different diameter diminishing in cubage with increase in diameter so disposed that the ring of greatest cubage and least diameter is within the other two and the ring of least cubage and greatest diameter is exterior of the other two, and disposed in planes so that the ring of greatest cubage and least diameter is in a plane different from the other two rings, and the three rings externally connected together for support with suitable means to

20 form a center means of connection to a drive shaft, internal connectors for the three rings comprising two conduits from the ring of least diameter to the ring of medium cubage a conduit from the ring of greatest diameter through the internal wall defining the least diameter of the ring of greatest cubage, all rings and connectors hermetically sealed.

2. A rotating refrigerating device comprising: three concentric hermetically sealed hollow rings containing a refrigerant, said rings being interconnected by hermetically sealed passageways comprising: a first passageway from the inner ring to the intermediate ring, a second passageway from the inner ring to the outer ring, a third return passageway from said intermediate ring to said inner ring and a fourth passageway from said intermediate ring to said outer ring, and means for rotating said rings.

3. The apparatus of claim 2 wherein said rings are externally secured together by blades, said blades forcing air past said rings when said apparatus is rotated.

4. The apparatus of claim 2 wherein said rings are concentrically mounted on a rotatable shaft.

5. The apparatus of claim 2 wherein said outer ring is insulated from said intermediate and inner rings.

45 6. The apparatus of claim 2 wherein said rings are mounted to revolve in horizontal planes, said inner ring being in a plane below said intermediate and said outer rings.

7. The apparatus of claim 2 wherein said third passageway is U-shaped at said intermediate ring.

8. The apparatus of claim 2 wherein the end of said fourth passageway terminating in said outer ring is jet shaped.

9. The apparatus of claim 2 wherein the portion of said outer ring between said second passageway and said fourth passageway is sealed.

55 10. The apparatus of claim 2 wherein said first passageway extends from said inner ring counterrotationwise to the inner periphery of said intermediate ring.

11. The apparatus of claim 2 wherein said inner ring is of greater volume than said intermediate and said outer rings.

60 12. The apparatus of claim 2 wherein a liquid of less volatility is sealed with said refrigerant.
